DESIGN FOR AN ENSEMBLE DRESS

Samuel Kane, Brooklyn, N. Y.

Application March 15, 1933. Serial No. 47,456

Term of patent 3½ years

To all whom it may concern:

Be it known that I, SAMUEL KANE, a citizen of the United States, residing at the borough of Brooklyn, New York city in the county of Kings and State of New York, have invented a new, original, and ornamental Design for an Ensemble Dress, of which the following is a specification, reference being had to the accompanying drawing, forming part thereof.

Fig. 1 is a front elevational view of an ensemble dress with a cape, showing my new design.

Fig. 2 is a rear elevational view of the same.
Fig. 3 is a front elevational view of the dress section of the ensemble dress.

Fig. 4 is a rear elevational view of Fig. 3.

I claim:

The ornamental design for an ensemble dress as shown.

SAMUEL KANE.
